(57) **CLAIM**

The ornamental design for a glider, as shown and described.

DESCRIPTION

FIG. 1 is a perspective view of a first embodiment of a glider showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is an elevational view of one side thereof, the opposite side being a mirror image thereof;

FIG. 7 is a perspective view of a second embodiment wherein one back support assembly of the glider thereof has been rotated to be in a facing relationship with the other back support assembly;

FIG. 8 is a front elevational view thereof, the rear elevational view being a mirror image thereof;

FIG. 9 is a top plan view thereof;

FIG. 10 is a bottom plan view thereof; and,

FIG. 11 is an elevational view of one end thereof, the opposite end being a mirror image thereof.
